(57) **CLAIM**

The ornamental design for a prescription bottle cap with dose noter, as shown and described.

DESCRIPTION

FIG. 1 is a perspective view of prescription bottle cap with dose noter showing the new design;

FIG. 2 is a perspective view of the uppermost portion of the prescription bottle cap of FIG. 1, shown separated from the prescription bottle cap for clarity of disclosure;

FIG. 3 is a perspective view of the mid-portion of the prescription bottle cap of FIG. 1 shown separated from the prescription bottle cap for clarity of disclosure;

FIG. 4 is a perspective view of the lowermost portion of the prescription bottle cap of FIG. 1, shown separated from the prescription bottle cap for clarity of disclosure;

FIG. 5 is a perspective view of the outer ring that fits over the lowermost portion of the prescription bottle cap of FIG. 1, shown separated from the prescription bottle cap for clarity of disclosure.

FIG. 6 is a top view of the prescription bottle cap of FIG. 1; FIG. 7 is a bottom view thereof;

FIG. 8 is a front view thereof;

FIG. 9 is a rear view thereof;

FIG. 10 is a right side view thereof; and,

FIG. 11 is a left side view thereof.

In the drawings, unshaded surfaces form no part of the claim.

The broken line showing of portions of the prescription bottle cap depicts environment and forms no part of the claim.
